UNITED STATES PATENT OFFICE.

ELIAS ISRAEL, OF NEW YORK, N. Y.

DESIGN FOR A CAP.

SPECIFICATION forming part of Design No. 28,050, dated December 14, 1897.

Application filed November 1, 1897. Serial No. 657,131. Term of patent 3½ years.

To all whom it may concern:

Be it known that I, ELIAS ISRAEL, a citizen of the United States, residing in the city, county, and State of New York, have invented and produced a new and original Design for Caps, of which the following is a specification, reference being had to the accompanying drawings, forming a part thereof.

In the said accompanying drawings, Figure 1 is a side view of a cap in which my design is embodied, and Fig. 2 is a plan or top view of the same.

The leading feature of my design consists in the series of curved or arched bands or stripes *a* of open-work, the crowns of the arches of said bands extending over onto the rounded or convex crown *A* of the cap.

As shown in the plan Fig. 2, there are four of the arched bands *a*, equally spaced and arranged about the body of the cap, the upright branches of said bands extending down to the lower margin of the cap-body.

What I claim is—

The design for a cap substantially as shown and described.

In witness whereof I have hereunto signed my name in the presence of two subscribing witnesses.

ELIAS ISRAEL.

Witnesses:

HENRY CONNETT,
PETER A. ROSS.
